UNITED STATES PATENT OFFICE.

SOLOMON K. KRAVER, OF MEDINA, OHIO, ASSIGNOR OF ONE-HALF TO ALLEN S. SEIBERLING, OF CLEVELAND, OHIO.

DESIGN FOR A FENCE-POST.

SPECIFICATION forming part of Design No. 30,795, dated May 16, 1899.

Application filed April 24, 1899. Serial No. 714,317. Term of patent 14 years.

To all whom it may concern:

Be it known that I, SOLOMON K. KRAVER, a citizen of the United States, residing at Medina, in the county of Medina and State of Ohio, have invented and produced a new and original Design for Fence-Posts, of which the following is a specification, reference being had to the accompanying drawings, forming part thereof.

10 Figure 1 is a plan view, Fig. 2 is a side elevation, and Fig. 3 is a front elevation, showing my new design.

As shown in the drawings, the leading or material feature of my design consists of an upright member A and a horizontal base member B, formed of an L-section, with a right-angle bend at C, one wing a of the upright part forming the front face of the post and extending backward at the bottom forms a 20 broad base b. Secured to the rearwardly-ex-

tending flange of the upright and to the upwardly-extending flange of the base is a diagonal brace D.

Standing out from the front face a of the post are a number of hook-shaped projections 25 c, the purpose of which is to receive and hold the wires or other longitudinal members of the fence.

Having thus described my invention, what I claim as new, and desire to secure by Letters 30 Patent, is—

The design for a fence-post, substantially as herein shown and described.

In testimony whereof I affix my signature, in the presence of two witnesses, at Medina, 35 Ohio, April 19, 1899.

SOLOMON K. KRAVER.

Witnesses:

LOUISE E. BUSHER,
FRANK SPELLMAN.
